Design 276.

Warneck, Leibrandt & Co.

Design for Portable Stoves

Patented March 26, 1850.

Ms. 376

C. W. Warnick, F. Leibrandt, J. G. Abbott
& A. Lawrence of Philadelphia Pa.

Letters Patent No. 276 - Dated March 26th 1850 -

The Schedule referred to in these Letters Patent and making part of the same,

To all to whom these Presents shall come:

Be it known, that we C. W. Warnick
F. Leibrandt, J. G. Abbott & A. Lawrence of Philadelphia, in the County of Philadelphia, and
State of Pennsylvania, have invented a new ornamental Pattern or Design, and that the following
is a full, clear, and exact description of the principle or character which distinguishes it from
all other things before known, and of the usual manner of making, modifying, and using the same,
reference being had to the accompanying drawing which shows a general view thereof -

This ornamental pattern, or design, consists of the following parts;
the lower plate has an oval hearth, projecting in front, with a double beaded moulding (a) inclosing
it with the bottom: the cylinder (part b) is fluted in vertical flutes, and is surmounted by a hollow
& round moulding at the top (c), above which there is a scalloped border (d), on which rests the top
grate (e), consisting of an outer and inner concentric circle, joined by curved bars; the top surface of the
whole being ornamented with oak leaves, and the legend Philadelphia Stove Works.

What we claim and desire to secure by Letters Patent, is
the above described ornament and illuminated design for portable furnaces.
